UNITED STATES PATENT OFFICE

2,532,258

ELECTRIC CIRCUIT INTERRUPTER

George F. Lincks, Pittsfield, Mass., assignor to
General Electric Company, a corporation of
New York

Application February 16, 1944, Serial No. 522,584

3 Claims. (Cl. 200—106)

1

My invention relates to electric circuit interrupters, and more particularly to such circuit interrupters which are adapted to be used in place of the conventional fuse cutout devices. Specifically my invention relates to a so-called fuseless cutout of the open type which may be either of the single element or reclosing type.

Fuse cutout devices have been used to a large extent in the protection of high tension electric distribution circuits. Devices of this kind in general heretofore have comprised replaceable fusible means usually located in close proximity to the high tension conductors. An abnormal electrical condition occurring on a circuit protected by a fuse cutout will destroy the fuse link and hence require replacement thereof. In modern practice on distribution systems several of these overcurrent protective cutout devices are connected in series thus demanding accuracy in order for proper correlation of such devices and so that each device performs its predetermined function. The need for renewal of the fuse link introduces the human element which, especially in a time of stress which is the time when fuse links blow, is apt to err by installing a fuse link of incorrect rating because the correct rating is not available. Also, although recent experimentation and research have reduced the cost of replaceable fusible elements, nevertheless such cost is still appreciable and it would be desirable to provide a fuseless cutout which would automatically interrupt the circuit under abnormal electrical conditions and yet wherein it is unnecessary to replace any fuse link after the protective operation of such cutouts, as is necessary with the fuse cutouts of the prior art. Also with reclosing fuse cutouts the clearing of temporary faults without service interruption is limited to the number of fuse links available for successive operation or to the ability of the operator to discover and to renew blown fuse links before an outage occurs. With the reclosing fuseless cutout it is unnecessary to manually replace any fuse links so that an unlimited number of temporary faults can be cleared without any attention by the operator.

My invention is related to the inventions disclosed and claimed in the copending applications of Sidney R. Smith, Jr., Serial No. 334,629, filed May 11, 1940, now Patent No. 2,424,126, July 15, 1947, and Serial No. 459,791, filed September 26, 1942, now Reissue Patent No. 22,744, April 9, 1946, both assigned to the same assignee as the present application, as well as to my prior copending application, Serial No. 388,864, filed April 16,

2

1941, now Patent No. 2,379,729, July 3, 1945, and also assigned to the same assignee as the present application.

It is an object of my invention, therefore, to provide a new and improved electric circuit interrupter adapted to replace the fuse cutouts of the prior art.

It is another object of my invention to provide a new and improved fuseless cutout which is simple and compact, economical in construction and which may be substituted for conventional prior art fuse cutouts.

It is another object of my invention to provide a new and improved fuseless cutout of the reclosing type, as disclosed and claimed in my copending divisional application, Serial No. 536,872, May 23, 1944, now Patent No. 2,472,625, June 7, 1949.

Further objects and advantages of my invention will become apparent as the following description proceeds and the features of novelty which characterize my invention will be pointed out with particularity in the claims annexed to and forming a part of this specification.

25 For a better understanding of my invention, reference may be had to the accompanying drawings in which Fig. 1 is a side view, partly in section, of a fuseless cutout embodying my invention with the contacts in the closed current carrying position; Fig. 2 is an enlarged view with certain portions omitted, partly in section, looking in the direction of the line 2—2 of Fig. 1; Fig. 3 is a partial view of a fuseless cutout similar to the one disclosed in Fig. 1, illustrating a modification of my invention; Fig. 4 is a view similar to Fig. 2 taken along the line 4—4 of Fig. 3; Fig. 5 is a view similar to Fig. 1 of a fuseless cutout of the reclosing type embodying my invention, and Fig. 6 is a view similar to Fig. 2 taken along line 40 6—6 of Fig. 5.

Referring now to Figs. 1 and 2 of the drawings, I have illustrated my invention in connection with an insulating support 10 of porcelain or other similar insulating material of a size and shape used in connection with the fuse cutouts of the prior art, such as is disclosed for example, in United States Letters Patent No. 2,354,907, Bennett et al., granted August 1, 1944, and assigned to the same assignee as the present application. Insulating support, or insulator 10 may be suitably supported from a pole carrying the transmission line (not shown) as by a supporting strap, mounting bracket, or hanger construction generally indicated at 11, which is adapted to surround a central portion of reduced diameter

12 of the insulator 10. Supported from the lower end of insulator 10 is the lower terminal contact assembly 13, to be described in greater detail hereinafter, which includes a movable contact 14. Cooperating with movable contact 14 is the stationary contact 15. In order to provide a satisfactory contact wipe the contact 14 is provided with a portion 14' biased toward contact 15 by spring 16. Contacts 14 and 15 comprise the relatively movable contacts of the circuit interrupter of my invention and contact 15 is illustrated as being mechanically supported from the upper end of insulator 10 by means of supporting arm 17. Contact 15 is furthermore electrically connected to line terminal 18 to which an external electric circuit such as conductor 19 may be connected.

It should be understood that insofar as my invention is concerned the relatively movable contacts 14 and 15 may be embodied in any suitable type of circuit breaker. As illustrated in Fig. 1, these contacts are embodied in an expulsion type circuit interrupter and contact 15 is mounted at the upper end of a tube of insulating material 20 which is suitably supported from arm 17 either by a permanent or readily removable means. Tube 20 is preferably at least lined with a material from which an arc extinguishing gas is evolved when subjected to the heat of an electric arc. Movable contact 14 is furthermore constructed in the form of a rod and reciprocally movable within insulating tube 20. Upon relative separation of contacts 14 and 15 by downward movement of rod contact 14 an arc is drawn in insulating tube 20. The heat of this arc causes gas to be evolved from the gas evolving surface within tube 20 to cause rapid extinction of the arc drawn and expulsion of the arc gases from the lower end of tube 20, which is open.

The lower terminal contact assembly 13 comprises a U-shaped support of conducting material 21, which is suitably fastened to insulator 10, as indicated at 21'. Electrically and mechanically connected to U-shaped conducting support 21 is a resilient contact supporting arm 22. This resilient contact supporting arm extends outwardly from insulator 10 in the same direction as support 17 and terminates in an upwardly extending portion 23 upon which rod contact 14 is supported. Resilient arm 22 might secure its resilience from a separate biasing means or may be formed of heavy wire preferably with a coiled portion 24 adjacent the supported end thereof to increase the resiliency and furthermore to constantly bias the contact 14 in a downward direction. Preferably resilient arm 22 is provided with a loop or eye 25 adjacent the contact supporting end thereof so as to be engageable by a switch stick for closing the circuit breaker, as will be described in greater detail hereinafter.

By virtue of the resilience of arm 22, means must be provided to latch the arm in the closed circuit position since otherwise contacts 14 and 15 will not remain in engagement. Supported from one end of the U-shaped conducting support 21 there is provided a latching means including the stationary backing member 26 which prevents the resilient member 22 from moving out of its normally latched position with respect to latch 27. Latch 27 is pivotally mounted to one end of U-shaped conducting support 21 as indicated at 28 and is biased in a counter-clockwise direction as viewed in Fig. 2 by spring means 29. The free end of latching member 27 indicated

5 at 27' and the free end of backing member 26 indicated at 26' are constructed in a diverging manner to insure movement of resilient arm 22 into latching position when moved upwardly by means of a maintenance tool, or the like, engaging eye 25.

10 A fuse cutout of the prior art will open the circuit on high currents due to melting of the fusible element. The fuseless cutout of my invention should operate in response to high currents and accordingly any suitable current responsive means may be provided for releasing latching means 27. This current responsive means has been specifically illustrated in Figs. 1 and 2 as of the electromagnetic type. Accordingly, in Fig. 1 there is disclosed electromagnetic means generally indicated at 30 comprising the magnetic structure 31, the winding 32 and the armature 33 biased to the upward position by means of a spring 34. This electromagnetic means 30 is supported on a suitable insulating member 35, which in turn is fastened to the other end of the U-shaped conducting support 21 as indicated at 36. One end of winding 32 is electrically connected as by means of conductor 37 with U-shaped conducting support 21, while the other end of winding 32 is connected to line terminal 38 which is connected to a suitable external circuit as illustrated by conductor 39. The current responsive setting of electromagnetic means 30 may be adjusted by varying the adjustment of a screw 40 which in turn varies the compression of spring 34 thereby requiring a higher current to move plunger, or armature 33, 20 downwardly if the compression of spring 34 is increased.

25 In order that electromagnetic means 30 may release latch 27 upon the occurrence of abnormal current conditions flowing in the circuit 40 19-39, armature 33 of electromagnetic means 30 is connected to a rod 41 which includes at the upper end thereof an elongated slot 42. An extension 43 rigidly connected to latching member 27 extends through the slotted opening 42 in such a manner that sufficient downward movement of rod 41 will cause clockwise rotation of extension 45 or arm 43 and consequently also of latch 27 to release resilient arm 22 and produce high speed separation of contacts 14 and 15. When the current flowing through contacts 14 and 15, resilient arm 22, U-shaped conducting support 21, conductor 37 and winding 32, which are all in series, reaches a sufficiently high value as determined by the electromagnetic means 30 and the adjustment of screw 40, armature 33 and consequently 50 rod 41 are pulled downwardly sufficiently to trip latching means 27 whereupon resilient arm 22 is no longer restrained and high speed separation of relatively movable contacts 14 and 15 results with the consequent interruption of the circuit. 55

60 Although I have illustrated the resilient arm 22 as forming a part of the lower terminal contact assembly 13, it will be obvious that it might just as well form a part of the upper terminal contact assembly. Also, although I have illustrated the tripping mechanism as being exposed to the weather, it is obvious that a suitable housing may be provided which could readily be supported on U-shaped conducting support 21.

65 Manual opening of the circuit interrupter disclosed in Fig. 1 may be accomplished by pulling downwardly on resilient arm 22 with sufficient force to release latching means 27, or by pulling 70 downwardly on extension 43. An appropri-

ate insulated maintenance tool would be used for this purpose. It would not be desirable, however, to open the circuit by pulling downwardly on a maintenance tool which engaged eye 25, since such action might interfere with the high speed opening of the circuit breaker after latch 27 has been released. The eye 25 is provided primarily for relatching the circuit interrupter in the closed position after it has operated. Such relatching is accomplished by merely moving resilient arm 22 upwardly until it is again latched in the position indicated in Figs. 1 and 2 with the contacts 14 and 15 in current carrying engagement.

It will be obvious that the electric circuit interrupter described above may replace the fuse cutouts of the prior art with the obvious advantage that a lineman can reclose the circuit upon operation thereof by merely pushing upwardly on resilient arm 22 without the necessity of replacing a part of the device, and without any reason for or opportunity to change the operating characteristics as by replacing an improperly rated fuse link in the fuse cutouts of the prior art. Furthermore, the downward position of resilient arm 22, which is visible from a considerable distance, will indicate that the circuit interrupter has operated and consequently no additional indicating means for this purpose is required.

It will be obvious that the current responsive means for operating the circuit breaker might comprise a bimetallic element instead of the electromagnetic means described in connection with Fig. 1. Accordingly, in Figs. 3 and 4 there is illustrated a modification of my invention in which the current responsive means is bimetallic instead of electromagnetic. The corresponding parts of Figs. 3 and 4 are designated by the same reference numerals as in Fig. 1. In this case the U-shaped member 21 of Fig. 1 may be replaced by an L-shaped member 44 with the lower end thereof terminating in a terminal 45 connected to an external circuit such as conductor 39. The resilient arm 22' is very similar to the resilient arm of Fig. 1. Supported from the end of conducting support 44 is a bimetallic latching means 46 which is quite similar in shape to the latching means 27 of Figs. 1 and 2. In order to insure that the current flows through the bimetallic means 46 the supported end of the resilient arm 22' is insulated from conducting support 44 as by insulating members 47 and 47'. The current flowing through movable contact 14 must therefore flow through the free end of resilient arm 22', then through bimetallic latching means 46 and conducting support 44 to terminal 45. A backing member 48 similar to the backing member 26 of Fig. 1 is provided. However, this backing member is provided with an insert 49 of insulating material which is normally in contact with resilient arm 22' so that when the circuit breaker is in the closed position no current can flow through the backing member 48 to conducting support 44 but all the current must flow through bimetallic latching means 46. However, between the time that bimetallic latching means 46 releases resilient arm 22' and the time that the arc is extinguished between relatively movable contacts 14 and 15, the backing member 48 must carry the current so that no arcing occurs between bimetallic means 46 and resilient arm 22'. Consequently the lower portion of backing member 48 is formed of con-

ducting material electrically connected with conducting support 44. The length of backing member 48 is of course dependent upon the contact separation of contacts 14 and 15 at which arc interruption is certain to have occurred.

With the circuit interrupter of Figs. 3 and 4 in the closed position all of the current must flow through bimetallic latching means or member 46 by virtue of insulating members 47 and 47' and insulating insert 49. When the current reaches a predetermined amount bimetallic latching member 46 is deflected sufficiently to release resilient arm 22' which begins to move downwardly at high speed to separate contacts 14 and 15. Slight downward movement of resilient arm 22' will cause it to electrically engage the conducting portion of backing member 48 so that the only arcing which will occur is within the expulsion tube 20 and which will be extinguished at high speed.

The operation of the arrangement disclosed in Figs. 3 and 4 will be obvious in view of the detailed description included above.

Although in Fig. 1 a compression spring 16 is provided to furnish a contact wipe, it should be understood that such contact wipe might be provided by the inherent resilience of arms 22 or 22' or of the tube supporting arm 17. In the arrangement described thus far the fuseless cutout must be manually reclosed after a circuit operation which corresponds to replacing the fuse in the fuse cutouts of the prior art. However, my invention is also adapted to be embodied in a reclosing type of fuseless cutout and a reclosing circuit interrupter embodying my invention is illustrated in Figs. 5 and 6, the corresponding parts being indicated by the same reference numerals as in Fig. 1. The circuit interrupting device shown in Fig. 5 is essentially the same as in Fig. 1. The lower terminal contact assembly, generally indicated at 50, comprises a conducting support 51 very similar to the U-shaped support 21 of Fig. 1. Resilient conducting arm 22 is electrically connected to conducting support 51, as indicated at 21'. The contacts 14 and 15 are held in the closed circuit position against the inherent action of resilient arm 22 which tends to move downwardly, by a latching means mounted on conducting support 51. This latching means comprises a backing member 52 and the latching member 53 which is pivotally mounted as indicated at 54 and biased in a clockwise direction, as viewed in Fig. 6, toward backing member 52 by spring means 55. Rigidly mounted to latching member 53 is an extension member 56 which is adapted to be engaged in the slot 57 of rod 58 connected to armature 33 of electromagnetic means 30. The construction described thus far is substantially the same as that shown in Fig. 1. Electromagnetic means 30 is mounted on an insulating member 59 very similar to the insulating member 35 of Fig. 1. This insulating member 59 is supported from conducting support 51 as indicated at 60.

In order automatically to reclose the circuit through contacts 14 and 15 upon opening thereof, it is necessary to provide means for applying an upward force to resilient arm 22 to cause it to relatch in the closed position. To this end I have provided resilient arm 61 provided with a coiled portion 61' so as to tend to move arm 61 in an upward direction. Arm 61 might comprise a rigid arm with separate biasing means

but is preferably made of heavy wire, heavier than that from which arm 22 is made, so that when arm 61 is free to move it is capable of forcing arm 22 to its closed circuit position. Arm 61 may be supported directly below arm 22 and as shown may be held in position by the same means which holds resilient arm 22 in position. Supported on the outer end of resilient arm 61 is a member 62 having forked end 62' for engaging resilient arm 22 during the circuit reclosing operation. In order to prevent resilient arm 61 from moving upwardly and continually holding resilient arm 22 in the closed circuit position, I provide a latch 63 comprising the pivotally mounted latching member 64 and the backing member 65. The latching member 64 is provided with a pair of extensions 66 and 67. The extension 66 is adapted to be engaged by spring 68 clearly shown in Fig. 6, which will hold the latching member 64 in either the open or closed position when moved to either of these positions. The latch 64 is adapted to be operated by engagement of the extension 67 with a rod 69 pivotally mounted at one end, as indicated at 70, to conducting support 51 and pivotally mounted at the other end, as indicated at 71, to the free end of resilient arm 61.

A member 72 rigidly fastened to rod 58 attached to the armature 33 of electromagnetic means 30 is adapted to engage arm 69. Member 72 may be positioned as shown in solid lines so as to cause downward movement of arm 69 immediately upon movement of rod 58 and armature 33 or may be positioned on rod 58 as indicated by dotted lines 72' so rod 58 can be pulled down more quickly to trip latch member 53 and free resilient arm 22 for opening contacts 14 and 15 and then member 72' can engage arm 69 so as to cause tripping of latch 64. Upon the occurrence of an abnormal current condition electromagnetic means 30 will not only trip latching member 53 in the same manner as occurred in Fig. 1 but in addition by virtue of member 72 and arm 69 resilient arm 61 would be pulled downwardly and stressed to an even greater extent than in the position shown in Fig. 5. Such downward movement of arm 69 will cause it to move latching member 64 to the open position by virtue of extension 67 and thereafter latching member 64 will be maintained in the open position until again engaged by arm 69 in its upward movement to the position indicated in Fig. 5. It can be seen that the position of member 72, whether it be the dotted line position indicated at 72' or the full line position indicated at 72, will control the initial tension of spring 34 armature 33 must overcome in order to pull rod 58 down and thus the time to effect the tripping of latch member 53. This would permit instantaneous opening of contacts 14 and 15 with member 72 in the dotted line position on rod 58 and maximum time delay with member 72 in the full line position on rod 58. A further control of the time delay is provided by spring 34 and screw 40 in the same manner as shown in Fig. 1.

It will be understood that means should be provided for delaying the reclosure of contacts 14 and 15 following the extinguishing of the arc therebetween. Accordingly, in Fig. 5 I have generally indicated a time delay and totalizing mechanism which is operated by a lever 73 pivotally connected to arms 61 and 69 as indicated at 74. This time delay and totalizing mechanism, generally indicated at 74, may com-

prise an escapement mechanism or any other suitable timing mechanism. I prefer to use a time delay and totalizing mechanism constructed in accordance with that disclosed in U. S. Letters Patent 2,069,082, granted January 26, 1937, and assigned to the assignee of the present application. Such a time delay and totalizing mechanism, after a predetermined number of consecutive operations would be arranged to lock the arm 69 in a downward position and consequently lock the circuit breaker in the open position, as in the above mentioned U. S. Letters Patent 2,069,082. In certain cases, however, it might be desirable to lock the circuit breaker in the closed position as disclosed and claimed in my copending joint application, Serial No. 468,522, filed December 10, 1942, now Patent No. 2,414,786, Jan. 21, 1947, and assigned to the same assignee as the present application. In accordance with the teachings of this copending joint application, the arm 69 after a predetermined number of consecutive operations would cause the contacts 14 and 15 to be locked in the closed position. It should be understood that the time delay and totalizing mechanism 74 may be any suitable mechanism and forms no part of the present invention insofar as the specific construction thereof is concerned.

In view of the detailed description included above, the operation of the reclosing circuit interrupter illustrated in Figs. 5 and 6 will be obvious. An abnormal current will cause armature 33 of electromagnetic means 30 to move downwardly. This movement will not only trip latching member 53 with the consequent interruption of the circuit at contacts 14 and 15 by the high speed downward movement of resilient arm 22 but will also pull resilient arm 61 and arm 69 downwardly. Downward movement of arm 69 will open latching member 64. As soon as the circuit is interrupted at contacts 14 and 15 armature 33 is free to move upwardly and is moved in that direction under the bias of spring 34. However, the time delay mechanism 74 prevents resilient arm 61 and arm 69 from moving upwardly at high speed, since a predetermined time delay is introduced. When this predetermined time has elapsed, arm 61 moves upwardly at high speed and since latch 64 is open it does not impede or stop the upward movement of resilient arm 61 whereupon resilient arm 22 is moved to its latched position and the circuit is closed at contacts 14 and 15. When arm 69 moves upwardly past the extension 67 of latching member 64, the latching member is moved to its latching position so as to latch resilient arm 61 when it again is moved to the position indicated in Fig. 5. However, if excessive current again flows through the circuit interrupter, armature 33 will be pulled downwardly so as to again trip open latch 64 and the reclosing and opening operations will function as hereinbefore described until the totalizing mechanism included in 74 locks open or locks closed the contacts 14 and 15 as described above. In performing such subsequent opening operations immediately following the initial reclosing operation which would occur in the event of a permanent fault, armature 33 must pull arm 69 as well as rod 58 for a greater distance than on the initial opening operation thereby introducing time delay in such subsequent opening operations. In any event rod 58 and arm 69 move downward sufficiently to permit resilient arm 22 quickly to separate contacts 14 and 15 the neces-

sary amount before latch 53 is tripped as hereinbefore described. Electromagnetic means 30, member 72 and arms 61 and 69 are so constructed that normal load current flowing through electromagnetic means 30 will be sufficient to latch arm 61 so that the fuseless cutout will reset to the initial operating position, shown in Fig. 5, after clearing a temporary fault from the line. Whenever resilient arm 22 moves downwardly, it engages the forked end 62' of the member 62 and rests therein until the reclosing operation is performed. Preferably the time delay and totaling mechanism 14 is such that after one, two or three successive reclosures and openings of the circuit breaker the arm 61 will be locked in either its open or closed position in accordance with the prior art referred to above.

While I have shown and described particular embodiments of my invention, it will be obvious to those skilled in the art that various changes and modifications may be made without departing from my invention and I, therefore, aim in the appended claims to cover all such changes and modifications as fall within the true spirit and scope of my invention.

What I claim as new and desire to secure by Letters Patent of the United States is:

1. A circuit interrupting device for use on high voltage distribution circuits comprising an insulating column-shaped support, a rigid arm fixedly mounted on and extending from one end of said support, an arc expulsion tube immovably fixed to the free end of said rigid arm, a resilient arm extending from said column-shaped support, one end of said resilient arm being immovably fixed to the other end of said support and extending outwardly therefrom, said arm being inherently resilient to cause relatively wide resilient movement of the free end thereof, a contact mounted on said rigid arm within said expulsion tube, another contact engageable with said first-mentioned contact mounted on said free end of said resilient arm so that the resiliency thereof constantly biases said contacts out of engagement, a support member of conducting material rigidly mounted on said other end of said column-shaped support and current responsive releasable latching means mounted on said support of conducting material and having an element electrically connected to said support, said latching means being engageable with said resilient arm to normally hold said contacts in engagement and responsive to a predetermined current through said contacts to release said resilient arm and permit separation of said contacts.

2. A circuit interrupting device for use on high voltage power distribution circuits comprising an insulating column-shaped support, a rigid arm fixedly mounted on and extending from one end of said support, a line terminal mounted on said rigid arm, an arc expulsion tube immovably fixed to the free end of said rigid arm, a resilient arm of conducting material extending from said column-shaped support, one end of said resilient arm being immovably fixed to the other end of said support and extending outwardly therefrom, said arm being inherently resilient to cause relatively wide resilient movement of the free end thereof, a contact electrically connected to said line terminal mounted on said rigid arm within said expulsion tube, another contact engageable with said first-mentioned contact mounted on said free end of said resilient arm so that the resili-

ency thereof constantly biases said contacts out of engagement, a U-shaped support of conducting material electrically connected to said resilient arm mounted on said other end of said column-shaped support, a second line terminal mounted on and electrically insulated from said U-shaped support, a releasable latch pivotally mounted on the free end of one of the arms of said U-shaped support engageable with said resilient arm to normally hold said contacts in engagement, and electromagnetic means mounted on the free end of the other arm of said U-shaped support and having a winding with the ends thereof connected respectively to said U-shaped conducting support and to said second line terminal, said electromagnetic means being responsive to a predetermined value of current through said contacts to disengage said latch from said resilient arm and permit separation of said contacts.

3. A circuit interrupting device for use on high voltage distribution circuits comprising an insulating column-shaped support, a rigid arm fixedly mounted on and extending from one end of said support, a line terminal mounted on said rigid arm, an arc expulsion tube immovably fixed to the free end of said rigid arm, a resilient arm of conducting material extending from said column-shaped support, one end of said resilient arm being immovably fixed to the other end of said support and extending outwardly therefrom, said arm being inherently resilient to cause relatively wide resilient movement of the free end thereof, a contact electrically connected to said line terminal mounted on said rigid arm within said expulsion tube, another contact engageable with said first-mentioned contact mounted on said free end of said resilient arm so that the resiliency thereof constantly biases said contacts out of engagement, a support member of conducting material rigidly mounted on said other end of said column-shaped support, a second line terminal mounted on and electrically connected to said conducting support and bimetallic means mounted on and electrically connected to said conducting support engageable with said resilient arm for holding said contacts in engagement, said bimetallic means being responsive to a predetermined current flowing through said contacts to effect disengagement from said resilient arm and permit separation of said contacts.
